(57) **CLAIM**

The ornamental design for an actuator vane shaft, as shown
and described.

DESCRIPTION

FIG. 1 is a front elevation view of an actuator vane shaft;
FIG. 2 is a left side thereof;

FIG. 3 is a rear elevation view thereof;

FIG. 4 is a right side view thereof;

FIG. 5 is a cross-section view thereof, viewed along line
2-2';

FIG. 6 is a top view thereof;

FIG. 7 is a bottom view thereof;

FIG. 8 is a top view thereof, shown within the unclaimed
environment of an actuator; and,

FIG. 9 is a front elevation view thereof, shown within the
unclaimed environment of an actuator.

The broken dashed lines (---) showing in FIGS. 1-7 are
included for illustrating portions of the actuator vane shaft
that form no part of the claimed design;

The broken long dash- short dash lines (- - -) showing in
FIGS. 8 and 9 are included for illustrating portions of the
actuator vane shaft that form no part of the claimed design;
while the broken dashed lines (- - -) are included for
unclaimed environmental structures.

1 Claim, 3 Drawing Sheets
